(57) **CLAIM**

The ornamental design for a door handle, as shown and described.

DESCRIPTION

FIG. 1 is a perspective view of a door handle showing the claimed design.

FIG. 2 is an opposing perspective view thereof.

FIG. 3 is an end view thereof.

FIG. 4 is an opposite end view thereof.

FIG. 5 is side view thereof.

FIG. 6 is an opposite side view thereof.

FIG. 7 is top view thereof.

FIG. 8 is a bottom view thereof; and,

FIG. 9 is a perspective view of the environment in which the door handle embodying the design is used. The broken lines in this Figure form no part of the claimed design.
